UNITED STATES PATENT OFFICE.

ABRAM EDWARD KAUFFMAN, OF EAST LIVERPOOL, OHIO, ASSIGNOR TO THE R.
THOMAS & SONS COMPANY, OF EAST LIVERPOOL, OHIO, A CORPORATION OF OHIO.

METHOD AND APPARATUS FOR FINISHING INSULATORS.

Application filed February 9, 1926. Serial No. 87,067.

My invention relates to an improved method and apparatus for finishing insulators, and particularly to insulators of the pin type. The object of my invention is to apply to a pre-shaped insulator, while still in plastic condition, a finishing operation which (1) prevents or minimizes distortion of the insulator during its subsequent drying; (2) works or "sizes" the surface of the insulator and thus creates a surface condition which greatly reduces or entirely avoids the danger of crack formation on subsequent drying; and (3) imparts an exact and substantially permanent shape which is retained by the insulator during the subsequent steps of its manufacture.

In the accompanying drawings—

Fig. 1 is a plan view of a tool for carrying out my finishing method;

Fig. 2 is a side elevation of the tool, and

Fig. 3 is a partial side elevation of the tool applied to the insulator.

As explained in the prior patent to Buckley No. 1,465,157, it has heretofore been suggested to impart a preliminary general shape to a plastic insulator blank by molding, and while still in plastic condition the blank has then been mounted upon a rotary spindle and a cutting tool has been used to accurately cut a peripheral groove in the head area of the insulator for the reception of a tie wire or the like. While an insulator formed in this fashion is accurately shaped when the cutter has finished its operation, I have found that the flange forming the upper wall of the groove has a tendency to sag and the groove become distorted during the subsequent drying. Moreover, there is a tendency to crack at the groove during the drying period, and the insulator is thus rendered defective. These difficulties result in a considerable wastage of both material and labor, thus enhancing cost of manufacture.

I have found that these troubles are practically eliminated if the blank, while still in plastic condition, is subjected to a finishing operation, such as hereinafter described. According to my invention, the blank is shaped to substantially its final form by a cutting tool which may be analogous to that disclosed in the Buckley patent above mentioned, but with the difference that the final contour of the groove and flange, while approached, is not fully attained. I then ap-

ply a finishing roller which is pressed against the blank while the latter is rotated. This roller kneads or works the surface of the blank, compacting the clay and imparting a smooth finish thereto, and at the same time gives the blank its desired final contour. The action of this finishing roller is thus quite different from that of the Buckley cutter, to which it is supplementary, and produces a finished article which is compacted and solidified at those areas at which there is danger of distortion; possesses surface characteristics which minimize or prevent the formation of cracks therein; and at the same time is accurately gauged to final shape.

The apparatus employed for this purpose may conveniently resemble, in many respects, the Buckley apparatus. Thus, it comprises a cap 15 shaped to fit upon and revolves with the head 16 of the insulator. Carried thereby, but swiveling with relation to the cap 15 is a hand grip 17 by means of which the cap 15 may be readily applied to the head of the insulator. A supporting arm 18 is pivoted on the stem of the hand grip 17, and a second arm 19 is pivoted at 20 to the arm 18. Detachably connected to the arm 19, and extending below the latter, is a hanger 21 which carries the grooving roll 22 which idles on the axis 23. A stop lug 24 projects from the arm 19 and bears against the margin of the arm 18 to limit the approach of the roller 22 toward the insulator. The periphery of the roller 22 is shaped to the desired finished contour of the groove 25 formed adjacent the head 16 of the insulator 26.

The operation is as follows. Following the operation of a cutter, such as that of the Buckley patent above mentioned, the cap 15 of the present finishing tool is applied to the rotating insulator 26, and thus accurately positions the tool upon the insulator. The arm 19 is then swung inward toward the insulator and the roller 22 enters the partially formed groove 25 into which it is pressed until the stop 24 is halted by its engagement with the arm 18. During its inward movement, after engaging the clay at the groove 25, the roller 22 kneads or compacts the clay at the surfaces engaged thereby, and its rolling frictional contact therewith produces a smooth, firm surface, which is resistant to cracking. Moreover,

it will be noted that the skirt of the cap 15 closely approaches, or substantially coincides with, the upper face of the roller 22; thus the material displaced upward by the roller is confined by the cap 15, so that the cap and roller co-act to densely compact the flange 27 forming the upper wall of the groove 25. This kneading and compacting of the clay in the flange 27 renders the latter structurally strong, with the result that during the subsequent drying operation there is no tendency of this flange to sag and deform the groove. The limit stop 24 gauges the depth of the groove 25, so that the latter is exactly formed to the desired depth. After the blank has been thus treated it is dried and glazed and baked in the usual fashion.

The detachability of the roller-carrying hanger 21 from the arm 19 makes it possible to substitute rollers of different shape and contour, as may be desired for different types of insulators. The precise peripheral outline of the roller may be varied, as also the shape of the cap 15. It is also obvious that the particular shape or type of insulator may be varied, since the advantages of my process are not restricted to any particular insulator outline. The thought which underlies my invention is embodied in the treatment of any insulator while in plastic condition, to which approximately final shape has been imparted, so long as the operation thereon comprises applying

to the plastic blank a finishing roller which 35 kneads the clay into its final shape, compacts it at the surface, and simultaneously imparts a smooth surface finish thereto. With this understanding I claim as my invention—

1. A finishing tool for plastic insulator blanks, comprising a cap adapted to be applied to an insulator head, and an associated swinging idler roll adapted to be pressed against the side of the blank adjacent the 45 cap, and to coact with the latter in compacting and shaping the material of the blank in the neighborhood of the cap.

2. The method of forming a ceramic insulator which comprises molding plastic ceramic material to the general contour of the insulator, cutting to shape a groove in the neck of the insulator blank, and working the grooved area to compact, smooth and shape 50 the latter to finished contour.

3. The method of forming a ceramic insulator which comprise shaping plastic ceramic material to the general contour of the insulator provided with a neck groove, and working the material in the grooved area 55 against restraining pressure applied to the insulator top, whereby the material in the area of the groove is compacted, smoothed and shaped to finished contour.

In testimony whereof I have signed my 65 name to this specification.

ABRAM EDWARD KAUFFMAN.
